UNITED STATES PATENT OFFICE

2,402,004

PORTABLE SPOT WELDER

Robert Earl Adams, Vancouver, Wash., assignor
to George H. Buckler, Portland, Oreg.

Application April 10, 1945, Serial No. 587,563

4 Claims. (Cl. 219—4)

1

The present invention relates to welding tools and more particularly to a light weight, portable spot welding gun.

Objects of the invention include providing an efficient and easily handled welding gun which can be easily and inexpensively made, largely from standard stock material, which will be certain, durable, safe and foolproof in operation, and which will be capable of being used in a wide variety of operations.

A particular field of utility comprises preliminary tacking of more or less light sheet metal or other parts preparatory to finishing the same by arc, spot or other type of welding. The new device is particularly adapted to such use because of the ease with which it can be handled and the versatility with which it accommodates itself to inconvenient and generally hard-to-reach locations.

A principal feature of the device resides in the use of a pistol type of grip and trigger by which the gun may be held in and operated by one hand, leaving the operator's other hand free to hold the work, adjust its position, or for any other purpose.

A related object is to provide means for holding the tool and for putting it into and out of operation, all in one hand of the operator, with the result that the operator's other hand is left free as hereinabove indicated.

Other and further objects and advantages of the invention are contemplated and will be recognized and appreciated by those skilled in the art.

For the purpose of illustrating the invention, which comprises the essential features of construction pointed out in the appended claims, I have shown in the accompanying drawing and shall describe in the present specification a certain embodiment which is now preferred by me because it has been fully tested and found in actual practice to give satisfactory and reliable results. In this connection it is to be understood that the several parts and elements which make up this embodiment may be variously arranged and organized within the scope of the invention and the claims and that the spirit of the invention is not limited to the precise details of the illustrated embodiment.

In the drawing,

Figure 1 is a bottom plan view of a gun embodying the invention;

Fig. 2 is a side elevational view, on a slightly reduced scale, of the device shown in Fig. 1;

2

Fig. 3 is a rear end elevational view of the device; and

Fig. 4 is a transverse section taken on the line 4—4 of Fig. 2.

As shown in these figures, a preferred embodiment of the invention comprises a pair of cooperating members which are hinged together and carry electrodes provided with welding tips which are swung toward and away from each other to start and terminate a resistance weld. The device is operated by trigger means which is compressed to bring the tips toward each other and is released to have them automatically retracted from each other.

The device preferably consists of an upper member 10 and a lower member 11, both made channel shaped out of some relatively hard, rigid dielectric material such, for example, as the canvas Bakelite composition known by the trade name "Micarta." The lower member 11 has attached to it, or made integral with it, a depending pistol type stock 12 of a convenient size and shape for gripping in the palm of the operator's hand.

The two members are hinged together by a pin 13 which is set through registering openings in a pair of upper hinge plates 14 riveted to the two outer sides of the upper member 10 and a pair of lower hinge plates 15 riveted to the two outer sides of lower member 11. These plates may be made of mild sheet steel of about one-eighth inch thickness, and of course it is important that the rivets be so arranged that the metallic elements 14, 13, 15 will not short circuit the electrodes which are adapted to be carried by the respective members, as will be hereinafter described.

The pin 13 may be maintained in its hinging position in any convenient manner, as by heading one end and drilling the other end portion for a cotter pin or the like.

Each of the members carries an electrode, such as that shown at 16 in the upper member and that shown at 17 in the lower member. Each electrode may be made of hard copper or the like, substantially square in cross section, as shown in Figs. 3 and 4, and it is convenient to rivet the electrode 16 directly to the upper member by rivets 18, and to secure the electrode 17 in the lower member by means of the same rivets 19 which fasten the lower hinge plate 15 in place. If the upper hinge plate 14 be fixed to the upper member 10 by rivets 20 which are spaced from the electrode 16, there is no possibility of short

circuiting the two electrodes by the plates 14 and 15 and any of the rivets.

The two members and their electrodes are kept normally expanded away from each other by a coil compression spring 21 which is interposed between the two electrodes and separated from each of them by an upper and lower insulating pad or shim 22 and 23.

Each electrode is provided with a front end bore in which a welding tip 24 is clamped, as by means of a nut and bolt combination or the like 25, and the rear end of each electrode is formed to receive a current supplying cable (not shown).

The two members are guided in their swinging movements toward and from each other by a pair of plates 26, conveniently made of the same material as the hinge plates 14 and 15, riveted to the sides of the lower member 11 and having the upper portion of each plate projecting up and overlapping the sides of the upper member 10, so as to provide a guideway for the upper member.

To keep the upper member from swinging out beyond the guideway just described, and to pull it down into the guideway when a welding spot is to be made, a pair of links 27 are connected, to each outer side of the upper member 10, by a hinge pin 28 which passes through the upper member, slightly in front of the guide plates 26. These links 27 project below the lower member 11 and are connected by a hinge pin 29 to the front arm 30 of a lever which is fulcrumed by a pin 31 mounted in an enlargement in the bottom of each guide plate 26. The rear arm of this lever is turned down and elongated to form a trigger 32 which normally stands away from the stock 12 but is juxtaposed thereto and can be pressed toward the stock when both are held in the operator's hand so that the forward arm 30 will swing down and the links 27 will pull the upper member down toward the lower member.

In this operation the tips 24 are moved toward each other from a limit of separation determined by engagement of the pin 29 with the bottom of the lower member 11, and when the approach is sufficiently close an arc is struck between them. This arc is extinguished when the trigger is released and the spring 21 moves the members and the tips toward their limit of separation.

The trigger 32 is conveniently made approximately as wide as the stock 12 and is curved to conform to the stock and the operator's hand, but is tapered and made thin where it is apertured to pass the pins 29 and 31. Bushings 33 may be used to center and position the trigger on these pins. It is convenient to make the trigger of bar stock with a plate of sheet metal welded or soldered to the front face of the depending rear arm, as shown in the drawing.

It is believed that it will be evident to those skilled in the art that the preferred construction hereinabove described embodies the principles of the invention as pointed out in the appended claims and achieves the objects and advantages set forth in the introduction to this specification.

I claim:

1. A spot welding hand tool comprising a lower member having a depending pistol type stock, an upper member hinged to the lower member near the rear portions of both members, electrodes mounted in both members and adapted to swing relatively to each other in the same plane

upon hinging movements of the members, welding tips mounted in the forward portions of the electrodes, a trigger pivoted between its ends to the lower member and having forward and rear arms on opposite sides of the pivot, said rear arm being juxtaposed to the stock so as to be gripped therewith in the operator's hand, link means connecting the forward arm of the trigger with the upper member between the welding tips and the point at which the members are hinged together, and a spring acting in tension between the member mounted between said point and the tips.

2. A spot welding hand tool comprising a lower member having a depending pistol type stock, an upper member hinged to the lower member near the rear portions of both members, electrodes projecting forwardly and rearwardly from both members and adapted to swing relatively to each other in the same plane upon hinging movements of the members, welding tips mounted in the forward projecting portions of the electrodes, lead connections formed on the rear projecting portions of the electrodes, spring means urging the members apart to separate said tips, a trigger pivoted between its ends to the lower member and having one arm juxtaposed to the stock so as to be gripped therewith in the operator's hand, and link means connecting the other arm of the trigger to a point on the upper member between the tip thereof and the hinge between the two members.

3. A spot welding hand tool comprising a lower member having a depending pistol type stock, an upper member hinged to the lower member near the rear portions of both members, electrodes mounted in both members and adapted to swing relatively to each other upon hinging movements of the members, welding tips mounted in the forward portions of the electrodes, spaced guide plates secured to the lower member and projecting at their ends above and below said member, said upper projecting portions forming a guide for constraining the upper member to swing in the plane of the lower member, a trigger having a fulcrum portion between its ends pivoted between the lower projecting portions of the guide plates and having one arm juxtaposed to the stock so as to be gripped therewith in the operator's hand, and link means connecting the other arm of the trigger to the upper member.

4. A spot welding hand tool comprising a lower member having a depending pistol type stock, an upper member hinged to the lower member near the rear portions of both members, electrodes mounted in both members and adapted to swing relatively to each other upon hinging movements of the members, welding tips mounted in the forward portions of the electrodes, spring means urging the members apart to separate said tips, spaced guide plates secured to the lower member and projecting at their ends above and below said member, said upper projecting portions forming a guide for constraining the upper member to swing in the plane of the lower member, a trigger having a fulcrum portion between its ends pivoted between the lower projecting portions of the guide plates and having one arm juxtaposed to the stock so as to be gripped therewith in the operator's hand, and link means connecting the other arm of the trigger to the upper member.

ROBERT EARL ADAMS.
